FRANK KARSCHITZ, OF BRIDGEPORT, CONNECTICUT.

COMBINATION-CHAIR.

1,305,221.

Specification of Letters Patent. Patented May 27, 1919.

Application filed March 5, 1919. Serial No. 280,737.

To all whom it may concern:

Be it known that I, FRANK KARSCHITZ, a subject of the Republic of Hungary, residing at 726 Pembrook street, Bridgeport, 5 county of Fairfield, State of Connecticut, have invented an Improvement in Combination-Chairs, of which the following is a specification.

This invention has for its object to provide a relatively inexpensive and very strong combination chair, which may be constructed almost entirely of angle and strap iron or steel, which may be easily adjusted to serve as a stationary chair, a swinging chair, or 15 a sleeping chair, the back and foot rest being capable of different adjustments in either of the above uses of the chair, and which shall be provided with a swinging member adapted to serve either as a table, or 20 as an inclined writing desk, or to be swung over so as to coöperate with the back and serve as a head rest when the chair is used as a reclining or sleeping chair.

With these and other objects in view I 25 have devised the novel combination chair which I will now describe, referring to the accompanying drawing forming a part of this specification and using reference characters to indicate the several parts.

30 Figure 1 is a front elevation, the swinging member being in position to serve as a table;

Fig. 2 a side elevation as seen from the right in Fig. 1, the swinging member appearing in full lines in use as a table, and in dotted lines in use as a writing desk;

35 Fig. 3 a fragmentary side elevation showing the back and foot rest in a reclining position, the swinging member being shown 40 in position to serve as a head rest; and

Fig. 4 is a detail perspective view partly broken away illustrating certain details of construction which will be hereinafter fully described.

45 The frame consists of two side pieces 10 made from strips of angle iron bent to the shape of a broad inverted U and braced by strips of strap iron, indicated by 11. 12 denotes standards extending upward from 50 the side pieces of the frame and formed from strips of strap iron bent to substantially the shape of an inverted V. The standards are braced near the top by cross pieces 13 and a cross piece 14 extends over 55 the tops of the standards, the ends of said cross piece being bent downward to form

lugs 15 in which a cross rod 16, from which the seat is suspended, oscillates.

The seat comprises side strips 17 of angle iron to which a board 18 is secured, and 60 arms 19 formed from pieces of strap iron, the ends of which are curved under the board and are secured between the angle flanges of the side strips and the board. The seat is suspended from cross rod 16 by means 65 of hangers 20, formed from strap iron, the ends of which are secured to plates 21 which in turn are secured to the arms. The mid-length of each hanger is looped about the cross rod and is secured thereto, the rod 70 oscillating in lugs 15 when the seat is swung. Below the cross rod, the sides of the hangers are riveted to a cross brace 22 which insures perfect rigidity of the swinging portion of the structure. 75

The foot rest comprises side strips 23 formed from strap iron and pivoted to the side strips of the seat, as at 26, the pivot ends being given a quarter turn and the ends extending beyond the pivots. The free ends 80 of said side strips are bent to form loops 24 in which the ends of a foot board 25 are secured. 27 denotes cross braces of strap iron extending between the side strips which complete and strengthen the foot rest. 85

The back comprises side strips 28, which are made of strap iron and pivoted to the side strips of the seat, as at 29, and cross pieces 30, which may be of wood. 31 denotes links, one end of each link being pivoted to the inner end of the corresponding side strip of the foot rest, as at 32, and the other end being pivoted to the corresponding side strip of the back, as at 33. These 90 links perform their usual function in reclining chairs and cause the back and foot rest to swing in unison, the foot rest swinging upward when the back is swung downward, and vice versa. The back and foot rest may be locked at any desired inclination 95 by means of a curved rack 34, one end of which is pivoted to one of the side strips of the back, the other end being adapted to slide through a keeper 35 which depends from one of the angle plates 36, which are 100 secured to arms 19 and serve an additional purpose which will presently be explained. The operation of the rack and keeper in connection with the foot rest and back will be clearly understood from Figs. 3 and 4. 110

The functions of table, writing desk and head rest are performed by a swinging

- member which comprises a U-shaped frame 37 made from strap iron and a board 38 which is pivoted, at one side of its longitudinal center, to swing vertically in the frame. The ends of the side strips of the frame are pivoted to the rear ends of angle plates 36, as at 52, so that the member may swing upward and under the cross brace 22 of the hangers.
- 10 The swinging portion of the structure, that is, the seat and coöperating parts, may be locked in place, either at the upright or a reclining adjustment by means of a swinging catch 39, which is pivoted to one of the standards, as at 40, and is adapted to engage a keeper 41 on the corresponding hanger.
- 15 In order to give additional rigidity to the structure, when used as an upright chair, I provide another swinging catch 42 which is pivoted on one of the side pieces of the frame, as at 43, and is adapted to engage a socket 44 between foot board 25 and the corresponding side strip 23.
- 20 In order to avoid all danger of the occupant of the chair getting a hand caught between a hanger and the corresponding standard, when the chair is swinging, I provide guards 45 which rest upon plates 21 just inside the hangers and are provided
- 25 with turn buttons 46 which are adapted to engage the hangers on the outer side thereof and thus retain the guards in place. These guards may be made of cross veneers of wood, so as to be relatively light. In fact
- 30 the structure as a whole combines lightness with great strength as well as convenience in operation.
- 35 These chair are made in different sizes and are equally adapted for children or adults. The smallest size is admirably adapted for use not only as a swinging or sleeping chair for small children but also as a "high chair," so called. In this use the swinging member is placed as in Figs. 1, 2
- 40 and 4, the side pieces of the frame resting in keepers 51 extending inward from the arms. The board 38 is placed in the position shown in Figs. 1, 2 and 4 in which the board lies horizontally and is held against being swung
- 45 downward by means of pins 47 in the sides of the board which engage recesses 48 in frame 37. In order to prevent the board from tilting upward a turn button 49 is provided on the under side of the board which
- 50 may be swung under one of the side pieces of the frame. In this position the board serves as a table and in order to prevent things from sliding off is provided with a rail 50 around its edge. The board may
- 55 also be fixed the same way in larger sized chairs, but for use by adults as an inclined reading or writing desk the board will be turned on its pivots and swung backward, as shown by dotted lines in Fig. 2, what
- 60 was previously the top of the board being

now the underside and resting against the end of frame 37. A ledge 53 is provided at the lower edge of the board to prevent books and papers from sliding off.

For use as a head rest or an extension of the back, the board is locked in place by the turn button, as described above, and the swinging member is swung over bodily, the board passing under cross brace 22 of the hangers, and the side pieces of the frame 75 are allowed to rest upon the top cross piece of the back, as in Fig. 3.

Having thus described my invention, I claim:

1. In a chair, the combination with a 80 swinging seat having arms, an adjustable back and an adjustable foot rest, of a swinging member comprising a frame pivoted to the arms and a board pivoted in the frame at one side of the longitudinal center of the 85 board, said board being adapted in its horizontal position to serve as a table, and when swung over so as to rest against the end of the frame to serve as an inclined writing desk, and the member being adapted to be 90 swung over bodily so that the side pieces will rest upon the back and the board will serve as a head rest.

2. In a chair, the combination with a 95 swinging seat comprising side strips made of angle iron, a board secured thereto, and arms made of strap iron, of a back and a foot rest pivoted to the respective ends of said side strips, said back comprising side strips made of strap iron and cross pieces, 100 and said foot rest comprising side pieces made of strap iron and a foot board, links connecting the side strips of the back and the foot rest, and a swinging member adapted to serve either as a table, an inclined desk 105 or a head rest, and comprising a frame made of strap iron and a board pivoted in the frame at one side of the longitudinal center of the board.

3. In a chair, the combination with a 110 swinging seat having arms, a back and a foot rest pivoted to the respective ends of the seat, and links connecting the back and the foot rest so that they will swing in unison, of a swinging member pivoted to the 115 arms and comprising a pivoted board, and means for supporting said board in position to serve either as a table, or a head rest, or in an inclined position to serve as a desk.

4. In a chair, the combination with a 120 swinging seat having arms provided with keepers, a back and a foot rest pivoted to the respective ends of the seat, links connecting the back and the foot rest, a swinging member pivoted to the rear ends of the arms, said 125 member comprising a frame and a board pivoted to the frame at one side of the longitudinal center of the board, said frame being adapted to engage the keepers to retain the member in a horizontal position, 130

and means for locking the board to the frame.

5. In a chair, the combination with a frame made of angle iron and braces made of strap iron, of standards extending upward from the frame, hangers suspended to swing from the standards, said hangers and standards being made of strap iron, a seat secured to the hangers, a swinging back and 10 a swinging foot rest pivoted to the seat, links connecting the back and a foot rest, and a swinging member comprising a frame and a board pivoted therein at one side of its longitudinal center.
- 15 6. In a chair, the combination with a frame, standards extending upward therefrom, a cross piece at the tops of the standards having downwardly extending lugs, and a cross rod mounted to oscillate in the 20 lugs, of hangers secured to the cross rod, a seat secured to the hangers, a back and a foot rest pivoted to the seat, and a swinging member comprising a frame and a board

pivoted therein, and serving either as a table or an inclined desk and when swung into 25 engagement with the back, serving as a head rest.

7. In a chair, the combination with a frame made of angle iron, standards made of strap iron extending upward therefrom, 30 and hangers of strap iron suspended to swing from the standards, of a seat secured to the hangers and having arms, a back and a foot rest pivoted to the seat, links connecting the back and the foot rest, means for 35 locking the back and foot rest at different adjustments, a swinging member pivoted to the rear ends of the arms and comprising a frame, and a board pivoted therein and adapted to serve as a table or an inclined 40 desk, and when the member is swung over bodily to serve as a head rest, and means for locking the chair against swinging.

In testimony whereof I affix my signature.

FRANK KARSCHITZ.
